UNITED STATES PATENT OFFICE.

GIDEON W. GATES, OF DAVID CITY, NEBRASKA.

DESIGN FOR A VENDING-MACHINE CASING.

SPECIFICATION forming part of Design No. 36,031, dated August 26, 1902.

Application filed May 16, 1902. Serial No. 107,691. Term of patent 7 years.

To all whom it may concern:

Be it known that I, GIDEON W. GATES, a citizen of the United States, residing at David City, in the county of Butler and State of Nebraska, have invented and produced a new, original, and ornamental Design for a Vending-Machine Casing, of which the following is a specification.

The invention relates to a new, original, and ornamental design for a vending-machine casing; and it has for its object to provide a design of that character which will be ornamental and attractive.

The leading feature of the design resides in the design forming the subject-matter of the accompanying illustration.

The figure of the drawing is a perspective view of a vending-machine casing, showing my new and original design.

Referring to the drawing, 1 designates a

vending-machine casing consisting of a lower circular portion or base 3 and an upper portion, which is in the form of the head of a Japanese. The upper portion or head is provided with a front having the configuration 25 of the face of a Japanese with his mouth open and smiling. The casing is provided at the mouth 2 with an opening, and the upper portion or head is connected with the lower portion or base by a reduced portion or neck 4. 30

What I claim is—

The ornamental design for a vending-machine casing as herein shown and described.

In testimony that I claim the foregoing as my own I have hereto affixed my signature in 35 the presence of two witnesses.

GIDEON W. GATES.
